MECHANISM FOR CONTROLLING ROLLER
SHUTTERS OR LIKE CLOSING MEANS

Pierre Themasson, Fretigney, France, assignor to
Etablissements Ad. Mischler (Société à Responsabilité Limitée) Fretigney, France, a company
of France

Application March 23, 1949, Serial No. 83,024
In France March 30, 1948

5 Claims. (Cl. 74—216.5)

1

In shutters of the roller shutter type used in buildings it often occurs that the chain mechanism serving for the operation of such closing means is not entirely satisfactory, more particularly when the control chain is slack. In such a case, it happens frequently that the links carried along by the toothed pinion do not leave immediately said pinion in order to follow the general direction of the floating strand and are wedged either between the pinion and the casing of the driving mechanism or against the second link of the chain, which locks the shutter against operation.

My invention has for its object to avoid such a drawback and concerns a mechanism for controlling chain-operated shutters that cannot be wedged whatever may be the tensioning of the chain. According to the invention, the controlling chain is guided at the entrance into and outlet from the pinion inside two channels provided in the casing and a suitably shaped member is held in the latter between the two strands of the chain so as to disengage the chain links from the pinion as soon as they arrive into register with the channel in which they are to enter. Thus, even if the chain is very slack, it is impossible for the links of the strand that is about to leave the pinion and that is consequently more or less floating, to continue accompanying the pinion as it rotates or to rock in the direction of such a rotary motion and thus to be wedged inside the casing.

Preferably the casing is made of cast metal and includes a boss located between the entrance and outlet ends of the chain and adapted to cooperate with a similar boss provided on the casing cover in order to form guiding channels in the casing and to hold between the two strands of the chain an extracting member or anti-knot guide. A locking device actuated by a spring may be associated with the mechanism for holding same fast as soon as pressure is no longer exerted on the control crank.

The following description and accompanying drawings corresponding thereto are given by way of example and by no means in a limiting sense so that the invention may be readily understood, the different features appearing as well in the drawing as in the specification forming of course, part of the invention. In said drawings:

2

Fig. 1 is a view of the arrangement according to the invention, the chain being in position in its casing the cover of which has been removed.

Fig. 2 is a vertical cross-section through line 5 11—11 of Fig. 1.

Fig. 3 is an elevational view of the chain extracting member.

Fig. 4 is an axial section of the chain pinion.

Fig. 5 is a side view of the locking means.

10 Fig. 6 is an end view corresponding to Fig. 5.

In the embodiment illustrated in the drawing, the pinion 1 controlling the chain 2 advances in a casing 3 closed by a cover 4 that may be secured to said casing through any suitable means, for instance studs 5 passing through openings 6 in the cover and through which are inserted split pins 7. Between the two strands of the chain, bosses 3a and 4a of identical substantially triangular shape with a curvilinear base are provided 20 in register respectively on the casing and on the internal surface of the cover, so as to provide to either side thereof between the bottom of the casing and the internal plane surface of the cover two channels 8 and 9 wherein the driving strand 25 and the driven strand of the chain 2 may move. The concave curvilinear base of these bosses is designed in a manner such that the teeth 1a of the pinion 1 may rotate freely inside the casing at a small distance from this base.

30 To the triangular boss 3a provided in the casing is secured a rectangular projecting tenon 10 that engages a corresponding opening or recess in the cover boss, after passing through an also rectangular opening 11a provided in the spring 35 steel member 11 (Fig. 3) assuming also a triangular shape, that is thus held fast between the two strands of the chain. The pinion 1 is provided with two rows of teeth that are spaced axially and are located to either side of the triangular member 11 forming the chain extracting member, said member 11 assuming substantially the same outline as the bosses 3a and 4a while extending beyond the latter so as to engage the gap between the two rows of teeth of the pinion 45 over a part of the circumference of the latter.

Advantageously and as illustrated in Fig. 2, the mechanism includes locking means allowing the mechanism to be held fast and consequently providing for the closing of the shutter when the apparatus is released and allowed to operate of

itself. To this purpose, the double pinion 1 is cut in the surface of a sleeve 12 provided with a square shaped axial opening 13, opening outwardly in order to receive the square rod of the controlling crank and extending inwardly of the mechanism so as to rotate in unison with a flat U-shaped member 15a (Fig. 5) held in the bore or opening of the sleeve 12 and the arms of which are provided outwardly with two lateral tail-pieces 16. The sleeve 12, shown on a large scale in Fig. 4, is held outwardly inside a bore provided in a suitable boss of the cover 4 while its inner end rotates inside a circular groove 17 provided in the actual casing. The inner end of the sleeve 12 is provided moreover with four notches 18 (Fig. 4) arranged along two rectangular diameters and the breadth of which is slightly greater than the thickness of the tail-pieces 16 of the locking member 15. The latter are held in a groove 19 provided vertically inside the casing while a spring 20 bearing against the bottom of the casing urges the locking member constantly against the sleeve 12 carrying the pinion 1. To this end the recessed part 15a of said locking member assumes at its inner end a conical or pyramidal shape for centering the spring 20 that is held inside said recessed part.

The operation is as follows: when inoperative the locking member 15 is urged outwardly by the spring 20 whereby its tail pieces 16 engage two opposite notches 18 in the sleeve 12. The pinion 1 and its control chain are thus held fast against rotation by the locking member 15 that is in its turn held in the groove 19 of the casing (Fig. 2); when it is desired to make the mechanism operate, the square end of the crank that has a sufficient length is introduced into the opening 13 and there is exerted through said crank an inward thrust, so that the locking member 15 is shifted leftwards of Fig. 2 against the action of the spring 20 and its tail-pieces 16 move out of the notches 18, which releases the sleeve 12 carrying the control pinion for the chain. When the crank is released, the spring 20 urges the locking member 15 back into engagement with the sleeve 20 and the tail pieces 16 enter again the two opposite notches 19 and hold the closing means fast in their final position.

Supposing the rotation of the pinion is executed in the direction of the arrow F (Fig. 1), the strand 21 is stretched while the strand 22 remains slack. In standard mechanisms that include no extracting member and no guiding channel the links wound over the pinion 1 are not urged of necessity when the chain is slack in the direction of the slack strand 22 and they may during the rotation of said pinion be drawn along by the latter or fall back in the direction of the movement whereby they are wedged against the stretched strand 21 and lock the mechanism. In the arrangement according to the invention, the extracting member 11 that engages at the upper part of the pinion 1 the gap between the two rows of teeth on said member actually constrains the chain links to move off the pinion, whatever may be their direction of progression and it guides these links towards the corresponding channel, 9 in the case considered, which protects the chain against any wedging inside the driving mechanism.

Obviously many modifications may be brought to the above described control mechanism, in particular through substitution of equivalent technical means for those described without unduly

widening thereby the scope of the invention as defined in accompanying claims.

What I claim is:

1. A chain mechanism chiefly for the control of roller shutters comprising a chain, a pinion driving same, a casing enclosing the pinion and cooperating portion of the chain and means for defining inside said casing separate channels for guiding two strands of the chain engaging said pinion and constituted by a triangular member having a slightly concave edge registering with the portion of the pinion lying between the two points of engagement of the chain strands with said pinion, the two other substantially rectilinear sides of the triangular member lying in the plane of, in parallelism with and at a small distance from the chain strand elements engaging the pinion and moving of same.

2. A chain mechanism chiefly for the control of roller shutters comprising a chain, a pinion driving same, a casing including a boss projecting between the ends of the chain strands that are about to engage and that have just moved off the pinion, a cover for the casing including a cooperating boss matching the shape of the first boss, said bosses defining with the inner wall of the casing, guiding passages for the chain ends considered.

3. A chain mechanism chiefly for the control of roller shutters comprising a chain, a pinion driving same, a casing including a boss projecting between the ends of the chain strands that are about to engage and that have just moved off the pinion, a cover for the casing including a cooperating boss matching the shape of the first boss, a thin extracting plate fitted between the two bosses, said bosses and extracting plate assuming a substantially triangular shape elongated in the direction of the gap between the chain strands and the end of which facing the pinion matches substantially the shape of said pinion and lies at a small distance from its periphery.

4. A chain mechanism chiefly for the control of roller shutters comprising a chain, a pinion driving same and provided with two axially shifted rows of teeth engaging the chain, a casing including a boss projecting between the ends of the chain strands that are about to engage and that have just moved off the pinion, a cover for the casing including a boss cooperating with and matching the shape of the first boss, a thin extracting plate fitted between the two bosses, said bosses and extracting plate assuming a substantially triangular shape that is elongated in the direction of the gap between the chain strands the end of which bosses and extracting plate facing the pinion matches substantially the shape of said pinion and lies at a small distance from its periphery for engagement between the two rows of teeth of said pinion.

5. A chain mechanism chiefly for the control of roller shutters comprising a chain, a pinion driving same, and provided with two axially shifted rows of teeth engaging the chain, a casing including a boss projecting between the ends of the chain strands that are about to engage and that have just moved off the pinion and a stud on said boss projecting outwardly, a cover for the casing including a cooperating boss matching the shape of the first boss, a thin extracting plate fitted between the two bosses and provided with an opening fitted over said stud on the first boss, said bosses and extracting plate assuming a substantially triangular shape elongated in the di-

5

rection of the gap between the chain strands, the end of which triangular bosses and plate facing the pinion matches substantially the shape of said pinion and lies at a small distance from its periphery for engagement between the two rows of teeth of said pinion.
